UNITED STATES PATENT OFFICE.

JAMES M. TRINER, OF CHICAGO, ILLINOIS.

ROTARY VALVE MECHANISM FOR GAS-ENGINES.

1,185,078.

Specification of Letters Patent. Patented Apr. 13, 1915.

Application filed February 26, 1912. Serial No. 679,972.

To all whom it may concern:

Be it known that I, JAMES M. TRINER, a citizen of the United States, residing at Chicago, in the county of Cook and State of Illinois, have invented certain new and useful Improvements in Rotary Valve Mechanism for Gas-Engines, of which the following is a specification.

My invention relates to improvements in valve mechanism for internal combustion engines, and the object of my invention is to provide an improved valve mechanism which will be simple and durable in construction, and well balanced and properly lubricated, which may be maintained in a cool condition and which will be positive and efficient in operation.

To the attainment of these ends and the accomplishment of other new and useful objects, hereinafter appearing, my invention consists in the features of novelty disclosed in the construction, combination and arrangement of parts herein described and claimed, and shown in the accompanying drawings, which illustrate one embodiment of my invention, and in which—

Figure 1 is a central, vertical longitudinal section of a four cylinder internal combustion engine embodying my invention; Fig. 2 is a transverse vertical section on line 2—2 of Fig. 1; Fig. 3 is a section similar to Fig. 2 of the upper portion of the engine, showing a modification of my invention. Fig. 4 is an enlarged view of the modified rotary valve member disclosed in Fig. 3; Fig. 5 is a sectional view similar to Fig. 3 showing still another modification of my invention. Fig. 6 is a sectional plan view on line 6—6 of Fig. 5.

In the drawings I have shown my invention as embodied in an internal combustion engine of the four cylinder type, but it will be obvious after having obtained an understanding of my invention from the disclosures herein made, that my invention may be embodied in and associated with various other types of engines, having a greater or less number of cylinders.

The structure shown is representative of an internal combustion engine, and, as is seen, has four cylinders 1, 2, 3 and 4 mounted on a common base or crank case 5. A main shaft 6 extends through and is suitably journaled in this case, and at its outer end carries the usual fly wheel 7. The main shaft has four angularly related cranks 8

to which the piston rods 9 are connected, as clearly shown in Fig. 1. The upper ends of these piston rods may be connected to working pistons 10, adapted to reciprocate in the cylinder chambers and to be actuated to drive the main shaft by the explosions of gas which take place in timed relation above the pistons. The angular relation of the cranks on the main shaft and sequence of explosions may be arranged in any suitable manner in accordance with established practice in the construction of engines of this character.

The walls 11 of the cylinders may be surrounded in the usual manner by water cooling jackets 12, as clearly shown in the drawings. In the structure shown each cylinder has an inlet port 13 and an outlet port 14. The inlet ports are preferably arranged in the walls of the cylinders adjacent their upper side portions, and the exhaust or outlet ports are preferably formed in the central portions of the top or upper end walls 15 of the cylinders. These ports may be of any suitable form found best adapted to the particular engine structure being manufactured, but I prefer that they be given an elongated rectangular form, so that in conjunction with the valve mechanism they may be quickly opened and closed. These ports are opened and closed in timed relation by means of rotary valves or members 16 and 17, adapted respectively to control the exhaust or outlet ports 14, and the gas inlet ports 13. While it will be obvious to one skilled in the art that these valve members may be constructed differently from each other to adapt them to the peculiarities incident to the exhaust and inlet ports, I prefer to make them practically identical in construction, except as to difference in size. For the sake of simplicity in construction and positiveness in time and operation, I prefer to make each of these valve members of a single piece of metal and common to the respective ports which they control; but it is obvious that they may, if desired, be made of a plurality of sections properly connected or related.

The upper portions of the cylinders are enlarged so as to form seats or chambers of circular cross section for the rotary valve members, and are arranged to entirely inclose the rotary valve members except at the points where the ports are located. This construction, as it will be seen, enables me

to provide a large wearing surface which insures the parts against becoming loose in time. This construction also possesses the advantage that the pressure caused by the explosions will be distributed over large valve seat area, and the warping or distortion of the valve members effectively eliminated. In addition to this practically all of the valve surfaces are sufficiently removed from the influence of the heat produced by combustion of the gases, that they may be properly lubricated. As a further precaution against destruction or damage by excessive heating I prefer to surround the valves and valve casings by water jackets 18 in which a flow of cooling water may be maintained. These water jackets may be, if desired, formed as a part of the water cooling jackets surrounding the cylinder.

The valve members 16 and 17 are provided with passages or port controlling openings 20 which are circumferentially or angularly disposed in accordance with the timed relation and sequence in which it is desired that the explosions take place and the cylinder operate, and the form and disposition of these passages may be determined by operating conditions and other factors entering into the construction of engines of this character. In Figs. 1 and 2 I have shown these passages as formed by cutting V shaped notches or slots in the peripheries of the valve members. These passages occupy preferably substantially 90 degrees of the sectional circle of the valve member, and are preferably of a length corresponding to the length of the ports which they control. When these valve passages are made in this form, I provide suitable inlets and outlets 21 and 22 with which, during their rotation, they are adapted to register and complete communication with the ports 13 and 14 respectively. As shown in Figs. 1 and 2, the exhaust outlets or passages 22 are laterally disposed above the cylinder heads in close relation to the outlet or exhaust ports 14, and are so arranged that any suitable piping may be connected thereto for the purpose of carrying off the exhaust gases and products of combustion. The gas inlet passages 21 are preferably disposed below the gas inlet valve 17, and may be connected to any suitable source of gas supply. These passages 21 are likewise arranged in close relation to the intake ports 13, so that communication therewith may be completed by the respective valve passages 20 during the rotation of the valve.

In the case of the modification shown in Figs. 3 and 4 it will be seen that the valve passages 20 are in the form of elongated rectangular slots or holes passing diametrically through the rotary valve members, and angularly arranged in accordance with the desired timing of the engine. In connection

with this form of valve passage the exhaust passages 22 and the gas inlet passages 21 are so arranged that when the valve passages 20 are in register with the outlet and inlet ports 14 and 13 the passages 22 and 21 will be in register with the valve passages 20, as clearly shown.

I sometimes find, under certain conditions, that extremely satisfactory results may be obtained by eliminating the gas inlet passages 20 and the exhaust passages 22 in the walls of the structure, and instead, making the valve members themselves hollow, as shown in Figs. 5 and 6. These tubular valve members, in addition to their functions as controlling valves, also serve to carry off the exhaust gases and convey to the cylinders the live gas mixture, as the case may be. In this case the valve members are preferably provided with sufficiently large interior passages 25 and 26 to serve the purposes for which they are intended. When the valve members are made tubular, as just described, I prefer that the port controlling passages or openings 20 communicate directly with the interior passages 25 and 26, and that they be sufficiently wide to properly permit the intake of gas or the outflow of exhaust. Any suitable method of connecting these tubular valves to supply the exhaust pipes 95 may be employed. In Fig. 6, however, I have shown a satisfactory construction by which these results may be accomplished. It will be seen that one end of each of the tubular valve members is provided with a V-shaped flange or rim 30, which fits within the enlarged internally threaded ends of a supply pipe 31 and an exhaust pipe 32. Into the enlarged ends of the supply and exhaust pipes I screw threaded collars 33 which engage the flanges 30 and take the end thrust on the valve member. If desired an additional locking collar 34 may be provided in each case to insure the collars 33 against becoming loose or unscrewing. This construction, while permitting the valves to rotate, forms sealed or gas-tight joints between the valves and the pipes connected thereto, and if desired, as a further precaution against leakage, suitable packing may be employed.

I find that excellent results are obtained by tapering the rotary valve members and their casings or seats; such, for instance, as shown in Fig. 6. This construction enables me to properly seat the valves in the event that they or their seats become worn. The tapering of these parts is advantageous whether the valves are constructed as shown in Figs. 1 to 4 inclusive, or whether they are of the tubular construction, as shown in Figs. 5 and 6. In order that the valve members may be secured in their adjusted position, I thread the portions of the valve members adjacent their ends, and provide thereon the threaded collars or nuts 35.

These collars may be locked in their adjusted positions by additional collars 36, as clearly shown in Fig. 6.

Any suitable driving mechanism may be employed for rotating the valves. The construction shown in the drawings, however, permits the use of a direct driving connection with the main shaft of the engine. The use of gears may thus be avoided by providing sprocket wheels 37 and 38 on the valve members and the main shaft of the engine respectively, and by connecting the corresponding sprockets by means of endless chains 39, preferably of the noiseless type. In the constructions shown in Figs. 1 to 4 inclusive, these driving connections for the valves may be connected at opposite ends of the engine, but in the construction shown in Figs. 5 and 6 it is advisable to place the driving connections for both valves at the same end of the engine in order to leave the opposite ends of the valve members free for connection with the exhaust and supply pipes.

It is thus seen that I have provided a simple and reliable valve mechanism capable of proper balance, lubrication and adjustment; which may be driven directly and positively from the engine shaft, and which eliminates the noise and other objections incident to puppet valves and their operating mechanism.

My invention is capable of embodiment in various other structures without departing from the spirit and scope thereof, and I wish it to be understood that I am not limited to the particular construction shown in the drawings.

What I claim as new is:

1. In an internal combustion engine, the combination of a cylinder having a port therein and a valve seat at said port; a rotary valve mounted in said valve seat and having one end extending therefrom; a supply pipe having its discharge end enlarged and said enlarged end embracing the

extending end of said valve; and means carried by said supply pipe locking the latter and said valve against relative movement.

2. In an internal combustion engine, the combination of a cylinder having a port therein and a valve seat at said port; a rotary valve mounted in said valve seat and having one end extending therefrom; a V-shaped peripheral flange on the extending end of said valve; a supply pipe having its discharge end enlarged and embracing the extending end of said valve, there being a seat in the enlarged end of said pipe engaging one side of said V-shaped flange; and a collar threaded in the enlarged end of said pipe, engaging the other side of said V-shaped flange and locking said supply pipe and valve against movement.

3. In an internal combustion engine, the combination of a cylinder having a port therein and a valve seat at said port; a rotary valve mounted in said valve seat and having one end extending therefrom; a V-shaped peripheral flange on the extending end of said valve; a supply pipe having its discharge end enlarged and embracing the extending end of said valve, there being a seat in the enlarged end of said pipe engaging one side of said V-shaped flange; a collar threaded in the enlarged end of said pipe, engaging the other side of said V-shaped flange, locking said supply pipe and valve against relative movement and sealing the joint between the supply pipe and valve; and a lock nut threaded in the enlarged end of said pipe and locking said collar against movement in said pipe.

In testimony whereof I have signed my name to this specification, in the presence of 85 two subscribing witnesses, on this 24th day of February, A. D. 1912.

JAMES M. TRINER.
